PAPER MAKING APPARATUS

Charles W. Howard, Franklin, Ohio, assignor to
 The Black-Clawson Company, Hamilton,
 Ohio, a corporation of Ohio

Application July 11, 1936, Serial No. 90,196

15 Claims. (Cl. 91—55)

This invention relates to waxed paper and the like.

One object of the invention resides in the removal of cooling water and the like from the 5 surface of a traveling sheet of waxed paper, the water removal being accomplished in an effective manner by a succession of shaving actions as the paper moves in a downward direction.

Another object is the removal of the water 10 from waxed paper and the like in such a manner as to minimize the broke loss.

Another object is the provision of apparatus including fixed blades for removing water from the surface of a waxed paper web and the like, 15 in which the construction is such as to facilitate rethreading the paper when a break occurs.

Another object is the removal of the water from waxed paper and the like without suction devices and other power requiring mechanism.

20 Another object is the provision of apparatus for removing water from the surface of a waxed sheet, comprising blades which are inclined downwardly and away from a downwardly moving sheet at a small angle to the sheet and at a 25 small angle to the vertical so that a comparatively small angular change takes place in the direction of movement of the particles of water as they leave the surface of the sheet, in order that the force of gravity is most effectively 30 utilized.

Other objects and advantages of the invention will be apparent from the following description, the appended claims and the accompanying drawings, in which—

35 Fig. 1 is a diagrammatic illustration of an apparatus embodying the present invention;

Fig. 2 is a side elevation of a water removal apparatus;

Fig. 3 is a front elevation of a portion of the 40 water removal apparatus;

Fig. 4 is a front elevation of a portion of the apparatus, on an enlarged scale;

Fig. 5 is a vertical section taken on the line 5—5 of Fig. 4;

45 Fig. 6 is a horizontal section taken on the line 6—6 of Fig. 5; and

Fig. 7 is a full size view of one of the shaving blades.

Referring more particularly to the drawings 50 by reference numerals, Fig. 1 illustrates a preferred embodiment of the invention in a rather diagrammatic manner. In this figure reference numeral 10 represents a reel of paper or other sheet material to which a coating of paraffin wax or the like is to be applied. The paper web

11 is guided over a guide roll 12 and to a pair of waxing rolls 13 which are arranged in or above a suitable tank 14 containing melted paraffin. The paper may be supplied directly to the nip of the rolls 13 or may be guided 5 beneath a submerging roll 15 to receive a wax coating on both sides. The waxed sheet moving on from between the nip of the rolls 13 is then passed into a cooling tank 17 containing cold water or other suitable cooling liquid, the submerging roll 18 causing the waxed paper to flow through the water so as to rapidly chill the wax and harden it. It is then very desirable to remove all of the water that clings as small globules or particles on both surfaces of the sheet. 15 Various ways have been attempted to remove this surface water before the waxed sheet is wound up in the form of a roll as indicated at 18, and one form of water removal apparatus that has been used to a large extent makes use 20 of suction to remove the surface water as the sheet passes upwardly from the cooling tank past suction pipes. However, such suction devices are expensive in construction and operation and offer certain objections which are 25 avoided in accordance with the present invention.

As herein shown, the waxed paper web moves upwardly from the water bath to an upper guide roll 20 provided near the upper end of the water 30 removal apparatus designated generally by the reference numeral 21. The water is removed from the surface of the web of waxed paper as the latter moves downwardly from the guide roll 20 to a lower guide roll 22, the latter serving to 35 guide the paper in a suitable manner for movement to the winding reel 18'. The two rolls 20 and 22 are suitably journaled in side frames 23, which may be suitable hollow castings having base portions 24 adapted to be mounted on the 40 sides of the water tank 17.

As the waxed paper moves downwardly from the roll 20 it traverses an upper series of blades 26, which are all adapted for shaving engagement with a light contact, with one side of the 45 paper and which operate successively to remove water particles from the waxed sheet by a combined shaving and gravitational action and without the use of suction devices. The blades 26, as shown, are so positioned that their shaving edges 50 collectively define a quite gradually curved line, see Fig. 2, although the line of downward movement of the paper does not depart to any large degree from a vertical line at any point along the water removal zone. There is preferably 55

some light pressure of the web against the blades, although the first blade or two of a series may be entirely out of contact with the paper if desired. The pressure of the paper against any 5 blade, however, is quite small due to the very gradual curve in which the web moves, as defined by the shaving edges of the blades.

Each of the blades 26 is a rather thin metal blade, preferably having a thickness of the order 10 of about one-sixteenth inch, having a thin sharp shaving edge, the blade surface presented toward the paper being inclined at a small angle to the paper and being inclined also at a small angle to the vertical. The side of the blade remote from 15 the paper and adjacent the blade edge is also preferably inclined at a small angle considerably less than 45° to the paper and to the vertical. The angle of inclination of the blades to the paper sheet may be as shown in the construction 20 illustrated in Fig. 7, where the paper facing sides of the blades are inclined at an angle of about 10° to the vertical while the sides of the blades remote from the paper and adjacent the blade edge is at an angle of about 20° to the vertical. These angles, however, may be somewhat 25 varied although the angularity of the blades to the paper should be comparatively small and less than 45° to obtain a very effective separation of the water from the paper as the paper 30 travels downwardly past a number of these blades. And with the angularity of the blades as above referred to, it has been found that any scraping action of the blades on the wax is not such as to cause scratches or marks on the waxed 35 sheet.

Quite a number of blades are utilized to completely remove the surface water from a side of a rapidly moving sheet of paper to such an extent that the wound up waxed sheet will be of 40 uniform appearance and will not be marred by spots caused by water drops or particles. Twelve such blades are illustrated in the drawings for each side of the sheet.

With the blades arranged as above mentioned, 45 the action of gravity is most effectively utilized, for the gravitational force on any particle of water on the sheet naturally tends to make that particle of water move in a downward direction and that natural tendency to move downwardly 50 is not interfered with to any large extent when the water particle comes in contact with a shaving blade. The direction of the water particle is merely changed through a comparatively small angle and still continues to move generally downwardly but it then moves along the surface of 55 the blade, to which it has a natural tendency to adhere because of the metallic character of the blade. Even though the blade may be very slightly spaced from the body of the paper as the paper moves past, the water would have a natural 60 tendency to cling to the metal blade and leave the wax. The water particle has no particular affinity for the waxed sheet, as the water does not tend to spread over or wet the surface of the waxed sheet, and readily attaches itself to the 65 metallic blade and continues its downward movement. It will also be understood that the first shaving blade with which the downwardly moving sheet contacts effectively separates a large 70 part of the water, and successive blades act successively to remove the remaining water particles, the removed water running down the inclined surface of the blades and being disposed of as will be presently described.

The air currents produced in accordance with

the arrangement described also assist the removal of the water, for the air movement following the rapidly traveling paper, and produced by the friction of the paper is deflected by the blades to move away from the paper and create 5 an entraining action tending to pull the water particles from the sheet just ahead of and at the point of contact between blade and sheet.

After the waxed paper has passed the upper series of shaving blades 26, it is engaged by a 10 second series of blades 27, which are similar in construction to the blades 26 but which incline downwardly and away from the opposite side of the sheet, to remove the water effectively from this opposite side of the sheet. The shaving 15 edges of the blades of the lower series, the angularity of the blades, and the number of the blades is preferably similar to the arrangement of the blades 26 except that the lower series is adapted for engagement with the opposite side 20 of the paper. As will be apparent from Fig. 2, the upper and lower series of blades together define a gradual reversed curve as the web moves from the upper roll to the lower roll 22 of the water removal apparatus.

The shaving blades 26 and 27 are preferably 25 detachably connected by suitable screws or the like to blade holders 28, as shown in Figs. 4, 5, and 6. The blade holders are preferably metal plates, having bolt receiving slots 29 which receive securing bolts 30, the latter extending vertically 30 through the various holders 28 and through spacing blocks 31 which are arranged between adjacent holders and which are preferably secured by fastening bolts 32 to a back plate 33. The back 35 plate 33 may be a suitable casting providing a common support for all of the blades 26 of the upper blade series, a similar plate being provided for the lower series of blades 27. These plates or supports 33 extend between and are bolted to the side frames 23 by means of bolts 35. As will be apparent, the slots 29 which are provided in the holders 28 permit lateral adjustment in the positioning of the blades so that the degree of curvature of the path of travel of the paper can be 40 altered, as desired, and so that the action of the various shaving blades may be equalized. The various attaching bolts 32 may be loosened, and with the bolts 30 loosened the position of the blade 45 holders 28 may be adjusted. When the bolt 30 is tightened the various holders are held fixed in 50 their relative positions and fixed with respect to the frame.

The water that is shaved from the paper passes 55 laterally along the holders 28 and into the chambers 36 of the side frames 23. Thus the water that is removed from the paper has no tendency to fall on some lower portion of the paper, but is returned directly to the tank 17 through the openings 37 in the base portion of the side frames.

Near the upper end of the water removal apparatus, the latter is provided with a curved plate 40 fixed to a tube 41 at the front and to a trough or tube portion 42. These tubes are secured at their opposite ends on the side frames 23 and communicate with the interior of the side frames. This plate is effective in catching any drops of water that are thrown by centrifugal force as the web passes upwardly and around the roll 20. Some of these drops move forwardly on the lower 60 surface of the plate and pass through a slot 45 in the upper side of the tube 41 and then move to the ends of the tube, through end channel or passage 43 and to the short horizontal passage 44 at each 65 end. The passage 44 extends to the inside of the 70 tube 41. The tube 41 is supported by a bracket 75

end frame. The water that moves to the rear on the plate 40 is collected in the trough or tube 42 and flows out the end of the tube into the side frames.

5 By reason of the grouping of those blades which engage one side of the paper, and having the blades which engage the other side of the paper so positioned as to become effective after the paper passes the last blade of the first series, the 10 paper can be curved in a gradual line, and if a break occurs in the paper it will be apparent that it is a very simple matter to rethread the paper over the upper roll 20 and past all of the blades and under the lower roll 22, the arrangement of 15 the blades in upper and lower series permitting this rethreading operation in an exceedingly simple manner. However breaks in the paper will not be frequent since any small defects in the paper, such as a small hole in the paper which 20 causes a projecting paper fragment are not apt to cause a break in the web. Any projecting particle would be so bent or cut by the first blade of a series that the other blades of that series would be without any effect tending to cause a break.

25 As will now be apparent the water or other cooling liquid can be removed from a waxed sheet by apparatus that does not require any additional power to be effective, the power required to pull the web through the waxing machine being utilized without requiring any additional suction devices and the like. This removal of the water is accomplished with a very small broke loss and produces a drier sheet than has been obtained in practice by the usual suction devices. When a 30 break in the paper does occur it is a comparatively simple matter to rethread the sheet, and as soon as the paper moves again the water removal immediately becomes effective.

While the method herein described, and the 40 forms of apparatus for carrying this method into effect, constitute preferred embodiments of the invention, it is to be understood that the invention is not limited to this precise method and forms of apparatus, and that changes may be 45 made in either without departing from the scope of the invention which is defined in the appended claims.

What is claimed is:

1. Apparatus for removing water and the like 50 from a web of waxed paper comprising means for guiding the web in a downward direction, and a series of shaving blades successively engageable with one side of the downwardly moving web, said blades inclining downwardly away from the web 55 and having shaving edges positioned in a gradual curve to gradually curve the path of travel of the web.

2. Apparatus for removing water and the like 60 from the surface of a web of paper comprising means for guiding the web in a downward direction, and a series of shaving blades successively engageable with one side of the downwardly moving web, said blades having shaving edges positioned to quite gradually curve the path of travel of the web and inclining downwardly away from the web at a small angle to the web and at a small angle to the vertical and removing the water from the web by a combined gravitation and shaving action.

70 3. Apparatus for removing water and the like 70 from a web of waxed paper comprising means for guiding the web in a downward direction, and a series of sharp metal blades successively engageable with one side of the downwardly moving web, said blades inclining downwardly away from the

web at a small angle to the web and at a small angle to the vertical and removing the water from the web by a combined gravitation and shaving action.

4. Apparatus for removing water and the like 5 from a web of waxed paper comprising means for guiding the web in a downward direction, an upper series of shaving blades successively engageable with one side of the downwardly moving web, and a second series of shaving blades 10 provided below the upper series and engageable with the other side of the downwardly moving web, the blades of each series having shaving edges positioned to define a gradually curved path of travel of the web, said blades inclining 15 downwardly away from the web.

5. Apparatus of the character described comprising means for guiding a web in a downward direction, an upper series of shaving blades successively engageable with one side of the downwardly moving web, and a second series of shaving blades 20 provided below the upper series and engageable with the other side of the downwardly moving web, the blades of each series having shaving edges inclining downwardly away from 25 the web.

6. Apparatus for removing surface material from a downwardly traveling web comprising an upper series of shaving blades successively engageable with one side of the downwardly moving web, and a second series of shaving blades 30 provided below the upper series and engageable with the other side of the downwardly moving web, the blades inclining downwardly away from the web and having shaving edges adapted for 35 substantial line contact with the web and positioned to quite gradually curve the path of travel of the web.

7. Apparatus for removing water and the like 40 from a traveling web comprising means for guiding the web in a downward direction, fixed side frames supporting said guiding means, a series of shaving blades fixed on said side frames engageable with one side of the downwardly moving web and inclining downwardly and away 45 from the web, and a second series of shaving blades fixed on said side frames engageable with the other side of the web and inclining downwardly and away from the web.

8. Apparatus for removing water and the like 50 from a web of waxed paper comprising means for guiding the web in a downward direction, an upper series of shaving blades successively engageable with one side of the downwardly moving web, and a second series of shaving blades 55 provided below the upper series and engageable with the other side of the downwardly moving web, a common supporting frame in which both said series are fixed, the blades of each series having their edges positioned to define a gradually 60 curved path of travel of the web, said blades inclining downwardly away from the web.

9. Apparatus for removing water and the like 65 from a web of waxed paper comprising means for guiding the web in a downward direction, and a series of shaving blades having water guiding surfaces inclining downwardly and away from the web at a small angle for effective mechanical separation of the water by a combined gravitation and shaving action.

10. Apparatus for removing water and the like 70 from a web of waxed paper comprising means for guiding the web in a downward direction, and a series of fixed shaving blades for each side of the paper each blade having a gradually taper- 75

ing shaving edge and having water guiding surfaces inclining downwardly and away from the web for effective mechanical separation of the water by a combined gravitation and shaving action.

11. Apparatus of the character described comprising means for guiding a coated web in a downward direction, a series of shaving blades inclining downwardly and away from the web 10 and effective to separate surface liquid from the web merely by a mechanical gravitational and shaving action, and a common support for said series.

12. Apparatus of the character described comprising means for guiding a coated web in a downward direction, a series of shaving blades inclining downwardly and away from the web and effective to separate surface liquid from the web by a gravitational and mechanical shaving 20 action, a common support for said series, and means for individually adjusting said blades on said support in a direction substantially transverse of the direction of web travel.

13. The method of removing water from waxed 25 paper by a combined gravitational and shaving action comprising moving the paper in a downward direction, and performing a succession of

shaving actions on the paper as the paper moves downwardly so as to mechanically separate the surface water from the paper by a change in direction of movement of the water particles through a small angle.

14. The method of removing water from waxed paper merely by a combined gravitational and shaving action comprising moving the paper in a downward direction, performing a succession of shaving actions on one side of the paper and then performing a series of shaving actions on the other side of the paper as the paper moves downwardly so as to mechanically separate the surface water from the paper by a change in direction of movement of the water particles 1 through a small angle.

15. The method of removing water from waxed paper merely by a combined gravitational and shaving action comprising moving the paper in a downward direction and in a very gradually 20 curved path and performing a succession of shaving actions on one side of the paper followed by a succession of shaving actions on the other side of the paper as the paper moves downwardly so as to mechanically separate the water from 25 the paper.

CHARLES W. HOWARD.
